(57) **CLAIM**

The ornamental design for interface connector receptacle, as shown and described.

DESCRIPTION

FIG. 1 is a front elevation view of the interface connector receptacle showing our new design;

FIG. 2 is a top plan view thereof;

FIG. 3 is a right side elevational view thereof, the left side elevational view being a mirror image;

FIG. 4 is a bottom plan view thereof;

FIG. 5 is a rear elevational view thereof;

FIG. 6 is a perspective view thereof; and,

FIG. 7 is a another angle of perspective view thereof.
